US00D526076S

(12) **United States Design Patent** (10) **Patent No.:** **US D526,076 S**
Krieger et al. (45) **Date of Patent:** **** Aug. 1, 2006**

(54) **LED AND COLD CATHODE FLUORESCENT LAMP**

D511,586 S * 11/2005 Yeh D26/37
D513,335 S * 12/2005 Lee D26/37

(75) Inventors: **Michael Krieger**, Miami Beach, FL (US); **Kevin Ellsworth**, Alva, FL (US)

* cited by examiner

Primary Examiner—Marcus A. Jackson

(73) Assignee: **Vector Products, Inc.**, Alva, FL (US)

(74) *Attorney, Agent, or Firm*—Venable LLP; Robert Kinberg; Manni Li

(**) Term: **14 Years**

(57) **CLAIM**

(21) Appl. No.: **29/239,437**

The ornamental design for a LED and cold cathode fluorescent lamp, as shown and described.

(22) Filed: **Sep. 30, 2005**

DESCRIPTION

(51) **LOC (8) Cl.** **26-02**
(52) **U.S. Cl.** **D26/37**
(58) **Field of Classification Search** D26/37-50;

362/157, 158, 171-174, 183-208
See application file for complete search history.

FIG. 1 is a perspective view from the front-top-left side of the LED and cold cathode fluorescent lamp showing our new design;

FIG. 2 is a front view of the design shown in FIG. 1;
FIG. 3 is a rear view of the design shown in FIG. 1;
FIG. 4 is a left side view of the design shown in FIG. 1;
FIG. 5 is a right side view of the design shown in FIG. 1;
FIG. 6 is a top view of the design shown in FIG. 1;
FIG. 7 is a bottom view of the design shown in FIG. 1; and,
FIG. 8 is a perspective view from the front-top-left side of the design with the cold cathode fluorescent lamp pulled out from the compartment and in a vertical position.
